SHOE PRESS PAD

William C. Card, Jr., Winthrop, Mass., assignor to
Compo Shoe Machinery Corporation, New York,
N. Y., a corporation of Delaware

Application August 8, 1933, Serial No. 684,165

7 Claims. (Cl. 12—38)

This invention relates to shoe presses of the type which are used in affixing soles to lasted uppers in the manufacture of cemented shoes, and more particularly to the inflatable pads used in such presses.

A general object of the invention is to provide a shoe press pad having generally improved characteristics which serve to facilitate the sole affixing operation and to insure elimination of defects in the quality of the work produced.

More particularly the invention has for objects the provision of a shoe press pad having a casing of improved configuration wherein stretch or distortion of the casing material is eliminated or materially reduced, with a consequent increase in the accuracy of attaching soles, and wherein the full benefit of the pressure in the pad is immediately made available along the entire bottom of the shoe.

20 A further object is to provide shoe press pads which are individually designed for exclusive use with right or left shoes.

Other objects of the invention will in part be obvious and will in part appear hereinafter.

25 The invention accordingly comprises an article of manufacture possessing the features, properties, and the relation of elements which will be exemplified in the article hereinafter described and the scope of the application of which will be indicated in the claims.

30 For a fuller understanding of the nature and objects of the invention reference should be had to the following detailed description taken in connection with the accompanying drawing, in which:

35 Fig. 1 is a plan view of a shoe press pad embodying features of the present invention and adapted for exclusive use with left shoes;

Fig. 2 is a side elevation of the pad of Fig. 1 viewed from the left of that figure; and

40 Fig. 3 is a side elevation of the pad of Fig. 1, viewed from the right.

Shoe presses for cement affixing soles to uppers are well known. The more modern presses usually comprise an inflatable air pad over which is disposed a shoe supporting or clamping means for holding the shoe assembly against upward displacement by the inflatable pad. These pads usually comprise an inflatable rubber bladder 45 encased in a suitable leather casing. In my co-pending application Serial No. 522,738, there is shown a shoe press wherein the shoe supporting means is adapted to be kept immovable during the loading operation, and wherein the pad is especially designed to cooperate with such a

supporting means. The pad of the present invention is adapted to be used in such a press, and in addition possesses characteristic features which render its use advantageous generally in all types of inflatable sole affixing presses.

5 As an inflatable shoe press becomes used in the factory, the leather casing of its pad gets broken in. That is, a pocket is formed in the shoe contacting part of its upper diaphragm in much the same manner that a pocket is formed in a baseball glove upon continued use. Lack of uniformity in the texture of leather results in pronounced stretch and distortion in many casings as they get broken in, and this fault is accentuated if both right and left shoes are promiscuously handled in the same press. Even when, through custom, the same press was repeatedly used for right shoes alone or vice versa, undue stretch and distortion was encountered because of the difficulty of adapting the casing surface 10 to both the outside and inside edge of the sole. It will be appreciated that the curve, elevation and general contour of the inside of an attached sole is considerably different from the sweep and curve of the outside, the former, among other 15 things, having its curve broken more closely toward the toe, and more abruptly. Faulty breaking in of the pads through stretch and distortion often results in lack of accuracy in attaching the soles, and sometimes causes the shoe to slant sideways in the jack, and also frequently compels the use of unduly high pressures to assure proper 20 accuracy and pressing contact between the sole and the upper.

25 In the present invention there is provided a 30 pad casing of a configuration which is especially adapted for use with left shoes alone, or with right shoes alone, as the case may be. In the drawing there is shown by way of illustration a left pad casing. It will be understood that the right casing will symmetrically correspond thereto.

35 Referring more particularly to the drawing, there is shown a casing generally designated 10 having an upper wall or diaphragm 11 and a bottom wall 12. These are spaced by vertical end walls 13 and 14 and by a left side wall or gusset 15 and a right side wall or gusset 16, the several 40 walls being suitably attached at their meeting edges by means of stitching, or the like. It will be understood that a suitable inflatable rubber bladder (not shown) is confined within the casing and is equipped with a suitable inflating and deflating conduit (also not shown). The pad is 45 adapted to be seated in the pad holding pocket 50

of a press such as that described in my aforementioned copending application Serial No. 522,738, or in or on any other convenient and suitable form of press.

5 The forward part of the pad, designated 17 and extending from the front edge thereof to the break line 18 at the ball of a shoe located thereover is the thinnest part of the entire pad. From this break line 18 the pad gradually thickens, reaching 10 its maximum thickness substantially medially of the shank portion, designated 19, and from thence decreasing in thickness to a line 20 located at the forward edge of the heel seat portion where it meets the shank portion. From this line, the 15 remaining portion 21 of the pad continues at a uniform thickness which is greater than that of forepart section 17 but is less than that of shank section 19.

The left side wall or gusset 15 is of uniform 20 vertical height from its forward end to the point 22 which is located approximately opposite the break line at the ball for the outside of the shoe. The right side wall or gusset 16 maintains a uniform vertical height from its forward height to 25 a point 23 which is approximately opposite the break at the ball for the inside of the shoe, and, as illustrated, is somewhat further forward than point 22 because of the difference in contour of the two sides of the shoe.

30 It will thus be seen that the pad is thinnest at its forepart portion, is thickest at the shank portion and is of intermediate thickness at the heel seat. These terms, "forepart", "shank", etc., as applied to the pad are of course intended to refer to those vicinities of the pad which are adjacent the named parts of a shoe placed thereover. The precision of their correspondence with the related parts of the shoe will depend upon the particular size of shoe used, it being possible, 35 however, to handle various sizes of lasts with satisfactory results.

An advantageous feature of the present casing resides in the fact that the right or inside side wall 16 is throughout of greater vertical height 40 and the curve or break from the forepart to the shank is more abrupt than in the corresponding portions of the left or outside side wall 15, as will be seen from a comparison of Figs. 2 and 3 of the drawing. That is, the casing is thicker on 45 the inside than on the outside, so that when the pad is in place on the press the upper wall of the casing in effect slopes from the inside downwardly toward the outside edge. This, especially when coupled with other novel characteristics of 50 the pad, is of great advantage. The provision of a pad of the kind described substantially eliminates faulty pad distortion, side slanting of the shoes, and other defects accompanying or attendant upon those mentioned. The inflatable 55 pressing surface which is presented against the

shoe sole is admirably fitted properly to affix the sole to the upper despite the troublesome configuration of the underside of the shoe. Better results as to accurate, yet speedy, mating of soles and uppers are obtainable with the present pad than with those heretofore in common use. The number of defective shoes produced is greatly minimized, while at the same time, the operator's work in registering and affixing the shoe parts is speeded and generally facilitated.

5 Since certain changes may be made in the above article and different embodiments of the invention could be made without departing from the scope thereof, it is intended that all matter contained in the above description or shown in the 10 accompanying drawing shall be interpreted as 15 illustrative and not in a limiting sense.

It is also to be understood that the following 20 claims are intended to cover all of the generic and specific features of the invention herein described, and all statements of the scope of the invention which, as a matter of language, might be said to fall therebetween.

Having described my invention, what I claim 25 as new and desire to secure by Letters Patent, is:

1. An inflatable shoe press pad for handling right or left shoes only, and having a thickened shank portion, said thickened portion being of greater longitudinal extent at the inside edge of the pad than at the outside.

2. An inflatable shoe press pad for handling right or left shoes only, said pad being thicker along its inside edge than along its outside edge.

3. An inflatable shoe press pad for handling right or left shoes only, said pad having its upper 35 shoe contacting surface sloping downwardly from the inside edge toward the outside edge.

4. An inflatable shoe press pad for right or left shoes only, including a casing having top and bottom walls spaced by lateral gussets, the inside 40 gusset being of greater height than the outside gusset.

5. An inflatable shoe press pad for right or left shoes only, including a casing having top and bottom walls spaced by lateral gussets, said gussets 45 being of greater height at the shank portion than at other portions of the pad, and the inside gusset being of greater height than the outside gusset.

6. An inflatable shoe press pad for right or left 50 shoes only, having its shank portion thickened across the entire pad, and having its inside edge thicker than its outside edge.

7. An inflatable shoe press pad for right or left 55 shoes only, having a thickened shank portion of greater longitudinal extent at the inside than at the outside of the pad, and having its inside edge thicker than corresponding parts of the outside edge throughout its length.

WILLIAM C. CARD, JR. 60
